UNITED STATES PATENT OFFICE.

GEORGE B. MILLER, OF GLOVERSVILLE, NEW YORK.

COAL-CAR COVER.

1,270,646.

Specification of Letters Patent. Patented June 25, 1918.

Application filed March 15, 1918. Serial No. 222,664.

To all whom it may concern:

Be it known that I, GEORGE B. MILLER, a citizen of the United States, residing at Gloversville, in the county of Fulton and 5 State of New York, have invented certain new and useful Improvements in Coal-Car Covers, of which the following is a specification.

This invention relates to railway rolling 10 stock, and more especially to freight cars; and the object of the same is to provide a cover which may be drawn up over and form practically a roof for an open-topped freight car such as contains coal. Experience has demonstrated the fact that when 15 it rains or snows on the coal while in transit, and then freezes, great difficulty is experienced in unloading the cars and even in dumping the contents thereof. My object 20 is to provide a cover for freight cars of this kind which will shed the rain and snow and thus avoid the difficulty mentioned.

This object is carried out by constructing the freight car cover in a manner hereinafter 25 more fully described and claimed and as shown in the drawings, wherein:—

Figure 1 is a side elevation and

Fig. 2 an enlarged cross section of a 30 freight car with this cover applied and one side drawn partly closed,

Fig. 3 is a detail of the hand wheel for operating the rollers.

Mounted on trucks T of any appropriate 35 type is an open-topped freight car comprising a bottom B and upright sides S and ends E of any appropriate size and character. In fact, it may have a dumping bottom, but I have not thought it necessary to illustrate the same. The sides probably will not have 40 doors such as are used in box cars.

In the application of my idea to such a car, the sides S are made of double walls so as to produce pockets as seen at 1 in Fig. 2 and these pockets constitute guides for the 45 flexible panels yet to be described. Above the pockets oblique guides 2 lead upward and are secured at 3 beneath a board 4 which forms the runway along the top of the freight car as usual. In Fig. 2 I have 50 shown how the end E is carried up to the guides 2 and may have an additional guide 2' if desired. Where said guides meet the top of the sides S, idle rollers 5 are mounted along the latter. Just beneath the board 55 and in appropriate bearings carried by it, winding rollers 6 are mounted, their trun-

nions 6' being extended through the car-ends and squared as seen in Fig. 3 so as to receive the squared hubs of hand wheels or cranks 7. Adjacent said squared ends the 60 trunnions carry ratchet wheels 8 adapted to be engaged by pawls 9 pivoted to the ends E of the car, thereby preventing a retro-grade movement of either panel after it has been drawn up in a manner to be described 65 below.

Wound upon the rollers are cables respectively numbered 10 and 11, and secured upon the cables are a number of slats 12 which are connected edge to edge so that they will 70 shed the elements as desired. These slats extend the whole length of the car as seen in Fig. 1 and collectively they make up a flexible panel for each side of the same, the panel being of sufficient height to fill the 75 pocket 1 when it is let down thereinto as seen in Fig. 1, or to cover at least one half of the roof and to extend past the roller 5 as seen at the left of Fig. 2. When a panel is let down, the top of the car is exposed, 80 but when the winding roller is rotated in the proper direction, its cables draw the panel upward, over the idle roller 5, until its upper edge comes beneath the board 4 so that in effect it forms a roof for the car-body. 85 The pawl-and-ratchet mechanism adjacent the hand wheel will be sufficient to hold the flexible panel in raised position, but if desired I may have other devices by means of which it may be locked in such position 90 when the car is completely covered, and thereby prevent unauthorized persons from gaining access to its load. In any case I would prefer that the latching and locking devices and the winding rollers stand beneath the 95 board 4 so as to be well protected thereby from the elements. In fact, said board may be said to constitute the ridge pole of a roof built over the open-topped car body. The sides S may be provided with outlets 20 100 through which there escapes what little water drips into or is loaded in with the coal, and when this improvement is applied the load of coal will reach its destination practically free from water and therefore 105 not frozen. If the latching or locking devices are used, they are then unlatched or unlocked. The pawls 9 are tripped, and the two sections of the cover permitted to run down over the idle rollers 5 by their own 110 weight until they are housed within the upright guides or pockets 1 and the top of the

car is open. The contents may then be shoveled or lifted out or unloaded in any appropriate manner, and as above suggested it may be possible to dump the load from 5 the bottom B if the latter be provided with dumping means. Hinged at 21 to the upper edge of the outer sides are boards constituting covers 22 which may be turned down and outward as seen at the left in Fig. 2 10 when the panels are raised, or may be turned over inward as seen at the right of Fig. 2 when the panels are lowered, their obvious function being to close the pockets 1 and prevent coal and extraneous matter from 15 collecting therein. These panels should be provided with notches 23 where the cables occur, as indicated in Fig. 1.

What is claimed as new is:—

1. In a car cover, the combination with 20 guides leading up the car sides and converging thence to a point above the transverse center of the car body; of flexible panels whose ends are mounted in said guides, winding rollers journaled in brackets carried near the apexes of said guides, cables leading from said rollers to the respective panels, and means for operating said rollers from the ends of the car.
2. In a car cover, the combination with 30 guides leading up the car sides and converging thence to a point above the transverse center of the car body; of flexible panels whose ends are mounted in said guides, a board supported at the apexes of said guides 35 and extending the full length of the car, winding rollers mounted in bearings beneath said board and having manual operating wheels at their ends, pawl-and-ratchet mechanism for holding the rollers against 40 movement in one direction, and cables attached to the rollers and leading to the respective panels, for the purpose set forth.
3. In a car cover, the combination with the

car body, idle rollers journaled along the upper edges of its sides, channeled guides 45 carried up the ends of its sides to an apex above the transverse center of the car body, and winding rollers journaled in bearings at said apex; of cables leading from said rollers outward over the idle rollers and thence 50 downward, slats secured to said cables and constituting two flexible panels, and latching means for holding said panels at said apex, as set forth.

4. The herein described car whose sides 55 have double walls producing upright pockets therein, guides carried by its ends and leading obliquely upward from the top of said pockets, a foot board extending longitudinally of the car above the upper ends of said guides, flexible panels whose extremities are movably mounted in said guides and whose bodies are adapted to be housed within said pockets, and operating mechanism beneath 60 said board for raising and lowering said 65 panels.

5. The herein described car whose sides have double walls producing upright pockets therein, guides carried by its ends and leading obliquely upward from the top of said 70 pockets, a foot board extending longitudinally of the car above the upper ends of said guides, flexible panels whose extremities are movably mounted in said guides and whose bodies are adapted to be housed within said 75 pockets, operating mechanism for raising and lowering said panels, and covers for closing the panels when they are lowered into said pockets.

In testimony whereof I affix my signature 80 in presence of two witnesses.

GEORGE B. MILLER.
